ALEXANDER A. FORDON, OF DETROIT, AND GEORGE LEWELLYN MORRISON, OF HUDSON, MICHIGAN.

COLLAPSIBLE BOX.

1,075,706.

Specification of Letters Patent. Patented Oct. 14, 1913.

Application filed November 29, 1912. Serial No. 733,990.

To all whom it may concern:

Be it known that we, ALEXANDER A. FORDON and GEORGE L. MORRISON, citizens of the United States, residing at Detroit, county of Wayne, and Hudson, county of Lenawee, State of Michigan, respectively, have invented a certain new and useful Improvement in Collapsible Boxes, and declare the following to be a full, clear, and exact 10 description of the same, such as will enable others skilled in the art to which it pertains to make and use the same, reference being had to the accompanying drawings, which form a part of this specification.

15 This invention relates to paper boxes and has for its object a box that is collapsible and that has a reinforcing member which serves to impart rigidity to the box when it is in position for service.

20 This box is especially designed for hats and the reinforcing member is drawn into position, as the box is opened out from a collapsed position, by the strings which tie the cover on and which may be used to 25 carry the box.

In the drawings:—Figure 1, is a view of the blank. Fig. 2, is a perspective of the inside of the box at one corner. Fig. 3, is a perspective of the box collapsing. Fig. 4, 30 is a plan view of the collapsed box. Fig. 5, is a vertical section of the box. Fig. 6, is a similar section showing the reinforced member drawn into position for service. Fig. 7, is a view of the blank from which 35 the cover is formed. Fig. 8, is a perspective of one corner of the cover. Fig. 9, is a similar perspective showing how the cover collapses. Fig. 10, is a plan view of the collapsed cover. Fig. 11, is a perspective 40 of the box with the cover in place.

The blank is scored parallel to its four edges by the lines *a*—*a*. These lines are set a distance from the edge equal to the height of the box that is desired to be constructed.

45 These parallel scorings cross forming the four gussets 1 that are diagonally scored by the lines *b*—*b*, so that each gusset is bisected to fold together as shown in Fig. 2. The sides 2 of the blank are diagonally 50 scored by the lines *c*, which substantially bisect the angles at the inside corners of the sides and extend to the edges. These scorings allow the collapsing of the sides inward, as shown in Fig. 3, so that the other 55 two sides of the box may fold down over

the sides. The gussets 1 are fastened to the sides 2 of the box by staples or other fasteners that are inserted at the top as shown in Fig. 2 at 3. Coöoperating with these gussets or corner-members at each 60 side is a reinforcing member or strip 4 which comprises a strip of stiff paper board, or metal may be used if desired. The ends are scored as at *d* by a diagonal scoring that registers with the scoring *c* when the 65 strip is in place at the bottom of the side 2. It is, therefore, evident that when the reinforcing member 4 is at the bottom of the side 2 that it is still held between the gussets 1 and the side 2 and yet it in no 70 way interferes with the collapsing of the box, as in Fig. 3. Its position at the bottom of the side 2 is shown in Fig. 5. There are a couple of perforations 5 in the strip and through these passes a cord 6, which passes 75 to the outside of the box through the two perforations 7 in the side 2 which are spaced apart the same distance as the perforations 5 and are in horizontal line, hence when both portions of the cord 6 are simultane- 80ously pulled through the hole 7, the reinforcing strip rises to the top of the box, as shown in Fig. 6 and is held in place by the gussets 1. It is, however, obvious that this reinforcing strip now counteracts the tendency of the sides to collapse along the scorings *c*. 85

By tying the two cords 6 (one cord being connected to each reinforcing strip) as shown in Fig. 11, the reinforcing strips are 90 held in their upper position where they are of service. It is apparent that when the box is carried by the cords 6 that the reinforcing strips will be forced to their uppermost position and hence the more strain on 95 the cords the tighter do the reinforcing strips engage with the gussets. These cords 6 serve also to tie the cover 8 upon the box. This cover 8 is scored parallel to its edges by lines *e*—*e*. Slits 9 are cut from the edges 100 to the intersecting point of each corner piece formed by the intersections of the scorings *e*—*e*. This allows the corner 10 to be folded around the adjacent side piece and fastened thereto by staples, as shown in Fig. 8. The 105 side member to which the corner piece 10 is integral is diagonally scored as at 11, so as to fold down upon the main portion of the cover and allow the adjacent side member to fold down over it and the main portion of 110

the cover. The position of the side members as they are part-way collapsed is shown in Fig. 9 and the cover in complete collapsed position, is shown in Fig. 10. It will, therefore, be seen that the cover may be collapsed into flat position as well as the box and hence the two may be shipped in a minimum of space.

What we claim is:—

- 10 1. A collapsible box comprising a rectangular blank, having parallel scorings forming the bottom and the sides of the box and forming portions intervening between the sides that are scored obliquely and which 15 form gussets that fold into the box, means for fastening the folded gussets to some of the sides, the said sides to which the gussets are folded having oblique scorings which allow the said sides to collapse and separate 20 reinforcing strips reciprocable between the bottom of the collapsible sides and the top of the collapsible sides, the said reinforcing strips being slidable between the scored sides and the gussets that are fastened there- 25 to, substantially as described.
2. A collapsible box comprising a bottom, sides, triangular gussets connecting two of

the sides to the other two sides and folded in and fastened to such two other sides, the said sides to which the gussets are fastened 30 being scored to allow them to collapse, separate reinforcing strips reciprocable between the collapsible sides and the adjacent gussets and a cord fastened to one reinforcing strip passing through a perforation in the 35 collapsible side and over the box to the adjacent side where it passes through a perforation and is connected to the other reinforcing strip on the opposite side whereby the reinforcing strips when at the bottom of the 40 sides do not interfere with the collapsing of the sides but when drawn up by the cord they prevent their collapsing, substantially as described.

In testimony whereof, we sign this specification in the presence of two witnesses:

ALEXANDER A. FORDON.
GEORGE LEWELLYN MORRISON.

Witnesses for Fordon:

STUART C. BARNES,
VIRGINIA C. SPRATT.

Witnesses for Morrison:

PERCY J. DILLON,
LELAND P. BEAL.
